SPECIFICATION forming part of Design No. 12,432, dated August 23, 1881.

Application filed July 14, 1881. Term of patent 3½ years.

To all whom it may concern:

Be it known that I, CHARLES MAGEE, of Williamsburg, in the county of Kings and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure *f* is a stripe containing a row of adjacent circular figures, apparently supported 15 on a series of upright figures.

The figure *E* is a stripe containing a band, *q*, ornamented with a series of open circular figures; also, the figure *p*, composed of a series 20 of daisy-like flowers separated by bands; also, the ornamented band *j*. The stripe *E* has also projecting into it the flowering branch *b* of the figure *H*. The stripe *D* contains this figure *H*, consisting of a cluster of large pointed leaves, from which projects the branch *b*, composed of 25 circular flowers and of buds. The figure *H* contains the figure *g*, consisting of two roses in bloom; also, the figure *h*, consisting of a branch with leaves and flowers resembling that of the lilac; also, the figure *e*, consisting of a leafy 30 branch extending over a figure shaped like a pillar; also, the figure *d*, a branch with leaves

and bunches of flowers thereon, from which, in turn, appears to project the large deeply-indented leaf *e*.

The figure *i* is a stripe ornamented with a 35 pattern somewhat resembling a close-set picket fence, upon which appear to grow bunches of flowers.

I claim—

2. The design for carpets, consisting of the stripe *E*, containing figures *q p j* and branch *b* of the figure *H*, substantially as shown.

3. The design for carpets, consisting of the 45 band *q*, substantially as shown.

4. The design for carpet, consisting of the figure *H*, containing figures *b g h c d*, and *e*, substantially as shown.

5. The design for carpets, consisting of the 50 stripe *i*, substantially as shown.

6. The design for carpets, consisting of the stripes *f* and *E*, substantially as shown.

7. The design for carpets, consisting of the stripe *f*, stripe *E*, containing figures *q p j* and 55 branch *b* of figure *H*, stripe *D*, containing figures *H g h c d e* and part of figure *b*, and stripe *i*, substantially as shown.
